UNITED STATES PATENT OFFICE.

ABROM D. BRUNER, OF ROCKWELL CITY, IOWA.

PLOW.

Application filed March 26, 1924. Serial No. 702,051.

To all whom it may concern:

Be it known that I, ABROM D. BRUNER, a citizen of the United States of America, and resident of Rockwell City, Calhoun

5 County, Iowa, have invented a new and useful Plow, of which the following is a specification.

The principal object of this invention is to provide an improved plow having a mold 10 board movable longitudinally, laterally and vertically relative to the path of travel, so that it will scour thoroughly and soil, no matter how sticky in character, will not stick to it.

15 A further object of this invention is to provide improved means for mounting movable members of a mold board for travel whereby movement is produced longitudinally, laterally and altitudinally.

20 This invention relates to and is an improvement on the invention described and claimed in Letters Patent of the United States Number 1,283,650 granted to me November 5, 1918, to which reference hereby 25 is made.

My invention consists in the construction, arrangement and combination of elements, hereinafter set forth, pointed out in the claims and illustrated by the accompanying 30 drawing, in which—

Figure 1 is a plan view and Figure 2 a side elevation of a plow embodying my improvements. Figure 3 is a vertical section substantially on the line 3—3 of Figure 1. 35 Figure 4 is a plan view of the elements shown in Figure 3. Figure 5 is an elevation showing a number of the traveling rods and their connections. Figure 6 is a vertical section, on an enlarged scale, on the line 6—6 of Figure 5.

40 Figure 7 is a view similar to Figure 5, showing a modified form. Figure 8 is a cross-section, on an enlarged scale, on the line 8—8 of Figure 7.

45 In the construction of the device as shown a share 10 and landside 11 are employed in the usual relation and are suitably connected with a beam (not shown) whereby draft is applied. A landside bracket 12 is 50 fixed at its forward lower end to the forward end portion of the landside 11 by means of bolts extending through holes 13 in said bracket, and said bracket extends upwardly and rearwardly on an arc to a 55 point between and elevated considerably relative to the rear portions of the land-

side and share 10. Associated with the bracket 12 is a curved bar 14 arranged beneath, spaced from and supported relative to said bracket as hereinafter set forth, and said bar is of less length than the bracket and terminates at both ends short of the ends of said bracket. A fieldside bracket 15 is arranged transversely and connected at its ends to the rear end portions of the share 10 and landside 11, and said bracket has at one end, adjacent the share 10, a bearing or support 15' for a spindle 16 which extends upwardly and forwardly therefrom in an inclined position, projecting through holes 17 in the curved bar 14 and bracket 12 and having at its upper end a head 18 contacting the outer surface of the latter bracket. The upper portion of the spindle 16 is threaded, and locknuts 19 are screwed thereon and engage respectively the lower surface of the bracket 12 and the opposite faces of the curved bar 14. A fieldside wheel 20 is rotatably mounted on the lower portion of the spindle 16 adjacent the support 15' and share 10, said wheel obviously being arranged in a plane inclined to the horizontal. Landside wheels 21, 22 are arranged for rotation between the upper or rear portions, and between the lower or forward portions, respectively, of the bracket 12 and curved bar 14, the wheel 21 being of considerably greater diameter than the wheel 22 and of somewhat less diameter than the fieldside wheel 20. The wheels 21, 22 are pivoted on nut equipped bolts 23, 24 respectively, mounted through and connecting the bracket 12 and bar 14, and said bolts, together with the locknuts 19, serve to support and maintain the curved bar relative to the bracket. An arched brace 25 is fixed at one end to the rear portion of the landside 11, adjacent one end of the bracket 15, extends upwardly and rearwardly and has its opposite end overlying the rear end of the landside bracket 12 and fixed thereto by the bolt 23. A shield 26 is mounted over the landside bracket 12 and suitably secured thereto and is of sufficient width to cover the wheels 21, 22, said shield being formed with a peripheral downwardly extending flange 27 projecting beyond and partially enclosing said wheels.

55 A movable moldboard for the plow is provided by means of a plurality of rods 28 carried at their lower ends by the fieldside pulley 20 and flexibly connected at their upper 60 65 70 75 80 85 90 95 100 105 110

ends and mounted for traveling engagement with the peripheries of the wheels 21, 22. Each rod 28 is formed at its lower end with a thickened portion 28' having a circular 5 aperture 29 therein (Figure 6) by which it is threaded on the rim of the fieldside wheel 20, which is of skeleton form, thus forming a pivotal connection between said wheel and the rods. There are enough of the rods 28 10 substantially to occupy all of the space circumferentially of the wheel 20 with their enlarged portions 28', and said rods spread out in something of a fan-shape from said wheel, and have their upper ends uniformly 15 separated and received within the flanged shield 26. The upper end portions of the rods 28 are reduced in diameter, at 28'', and are pivotally connected by means of links 29 in endless form. Each link 29 is formed of 20 an angle bar, as shown in section in Figure 6, and each link is formed at each end, in one of its flanges, with an aperture to receive the reduced portion 28'' of a rod, two such links being attached to each rod and extending 25 in opposite directions to adjacent rods, whereby a flexible, endless connection is formed between the outer ends of the rods. The links 29 are held in place on the rods 28 by means of pins or keys 30 mounted 30 through the rods, or in any other suitable manner. The other flanges of the angle-bar links 29 are arranged outwardly of the endless connection thus formed, and are in sliding contact with the inner face of the flange 35 27 of the shield 26. The endless traveling moldboard thus formed is adapted for travel on the respective wheels, the lower end being carried by the fieldside wheel 20 and the upper end by the landside wheels 21 and 40 22, the reduced upper ends of the rods being adapted for travel on the peripheries of said wheels as indicated in Figure 6.

In use soil displaced from the furrow by the share 10 will fall upon the movable 45 moldboard shown and described and the frictional contact therewith will cause the inclined surface above said share to travel rearwardly, longitudinally of the plow, and also upwardly or altitudinally, because of 50 the upward inclination of the rear side of the fieldside wheel 20, and also laterally in passing around the wheels, the rods 28 passing to the rear and then to the left around the wheels and then forwardly in succession. This traveling movement of the moldboard will discharge therefrom the furrow turned thereon under the plowing action, and thus prevent the soil from sticking 55 thereto, and the relative movement of the individual rods, in such movement, absolutely prevents the accumulation of any soil even in working in gumbo and insures a perfect scouring action.

In the form shown in Figures 7 and 8 an 60 addition is made to the traveling moldboard

in the way of substantially triangular shields 31 forming a connection between adjacent rods 28. The shields 31 are formed separately, of sheet metal or the like, and each substantially covers and fills the space between a pair of adjacent rods. Each shield 31 is formed at its upper end with an integral eye 32, formed of a tongue or strip of metal, embracing an upper portion of a rod 28, and at its lower end with a similar 70 eye embracing a lower portion of said rod just above the enlarged part 28', thus forming a pivotal connection between one long margin of the shield and the rod. The opposite long margin of each shield 31 is 75 formed with an integral projecting tongue 33 between its ends, overlapping upon a marginal portion of an adjacent shield, to prevent this margin of the shield from moving inwardly of the device. The shields 31 serve to form a relatively unbroken surface 80 for the movable moldboard and to prevent the entrance of dirt to the space within the same.

I do not desire to be understood as limiting myself to the precise construction and arrangement here shown and described, as various modifications may be employed, within the scope of the appended claims, without departing from the spirit of my invention.

I claim as my invention—

1. In a plow, a fieldside wheel and a pair of spaced landside wheels having different axes of rotation, and a plurality of rods 100 pivotally connected at one end to said fieldside wheel and having pivotal connections at their opposite ends and adapted for travel around said landside wheels.

2. In a plow, a support, a fieldside wheel journaled therein, a bracket, a pair of spaced wheels journaled in said bracket, and a plurality of rods pivotally connected at one end with the first wheel and diverging towards their opposite ends, together with means for flexibly connecting the last named ends of said rods, which ends are adapted for travel around said spaced wheels.

3. In a plow, a support, a fieldside wheel journaled therein, a curved bracket, a pair 115 of spaced landside wheels journaled in said bracket, a plurality of rods having pivotal engagement at one end with said fieldside wheel and diverging toward their opposite ends, links pivotally connecting the divergent ends of the rods, said links and adjacent ends of the rods being adapted for travel around said landside wheels.

4. In a plow, a support, a fieldside wheel journaled therein, a bracket, a pair of spaced landside wheels journaled in said bracket at different elevations, said fieldside wheel being inclined relative to the horizontal, a plurality of rods pivotally connected 125 at one end to said fieldside wheel, and flexi-

- ble connections between the opposite ends of said rods, the flexibly connected rods being adapted for travel around said landside wheels, whereby a longitudinal, lateral and altitudinal movement of the rods is produced.
5. In a plow, a support, a fieldside wheel journaled thereon in inclined position, a curved bracket having one end lower than the other, a pair of landside wheels journaled at opposite ends of said bracket, a plurality of rods threaded at one end on the rim of said fieldside wheel, a plurality of links flexibly connecting the opposite ends of said rods, the flexibly connected ends of said rods being adapted for travel on said landside wheels, and a shield mounted over
- and partially enclosing said landside wheels and the flexibly connected ends of said rods.
6. In a plow, a support, a fieldside wheel journaled therein, a bracket, a pair of spaced landside wheels journaled in said bracket, a plurality of rods pivotally connected at one end to said fieldside wheel, flexible connections between the opposite ends of said rods, the flexibly connected ends of said rods being adapted for travel around said landside wheels, and triangular shields flexibly connecting and covering the spaces between adjacent rods.
- Signed at Rockwell City, in the county of Calhoun and State of Iowa, this 8th day of March, 1924.

ABROM D. BRUNER.
